UNITED STATES PATENT OFFICE.

THOMAS A. JOHNSTON, OF CHADRON, NEBRASKA.

ROD-PACKING.

No. 872,132.

Specification of Letters Patent.

Patented Nov. 26, 1907.

Application filed May 2, 1907. Serial No. 371,447.

To all whom it may concern:

Be it known that I, THOMAS A. JOHNSTON, a citizen of the United States, residing at Chadron, in the county of Dawes and State 5 of Nebraska, have invented certain new and useful Improvements in Rod-Packings, of which the following is a specification.

This invention is a rod-packing, and has for its object to provide an improved packing 10 which will permit lateral motion or vibration of the rod without the efficiency of the packing being impaired.

In the accompanying drawing, Figure 1 is an end view of the invention. Fig. 2 is a 15 side elevation. Fig. 3 is a longitudinal section. Fig. 4 is a vertical section.

Referring specifically to the drawing, 1 denotes a stuffing-box which is in two sections indicated at 2 and 3, respectively. The sections are connected by bolts 5 passing through flanges 6 and are fastened to the cylinder head 4 in any suitable manner. On one side of the stuffing-box is a neck 7 having an opening 8 which communicates with 20 the interior of the box. The neck is threaded on the outside to receive a cap 9 for closing its outer end. The neck is also in two sections or halves one of which is on part 2 and the other on part 3 of the stuffing-box. The 25 threads on the neck sections are so arranged that their continuity will not be interrupted when the stuffing-box sections are assembled. The cap also assists to hold the sections together.

Within the stuffing-box is arranged a cylindrical casing 10 which is open at both of its ends and has a tubular stem 11 extending into the opening 8 of the neck 7 and also into the cap 9. The stem is threaded on the 30 side to receive a closing plug 12, and also contains a spring-pressed follower 12^a, the spring 13 being interposed between the follower and the bottom of the plug 12, the latter also serving to regulate the tension of the 35 spring 13. The casing 10 is spaced from the inner walls of the stuffing-box.

Inside the casing are arranged cup-shaped packing rings 14 and 15, respectively, the cupped ends of which face one another. 40 These rings project slightly beyond the ends of the casing and between said projecting ends and the end walls of the stuffing-box are interposed flat packing-rings 16 having an inside diameter slightly greater than the 45 diameter of the rod 17 so that they will not interfere with the vibration of said rod.

Against the cupped ends of the rings 14 and 15 are placed packing-rings 18 which are made conical at one end to correspond to said cupped ends and fit snugly thereagainst. 60 Between the rings 18 is a spring 19 for pressing said rings tightly against the rings 14 and 15. The inside of the casing 10 not occupied by the spring and packing-rings herein described will be filled with small shot or 65 spheres 20 mixed with graphite up to the follower 12^a. The shot or spheres will be of suitable antifriction metal or graphite and the like. The spring-pressed follower 12^a compresses the shot around the rod 17 and 70 takes up wear of that portion which is in contact with the rod. The rings 18 may be dispensed with if the packing is applied to non-vibrating parts.

The parts inside the casing form a steam-tight packing for the rod and effectively 75 prevents leakage, but if any such should take place it would be held in the stuffing-box. As the casing 10 is loose in the stuffing-box it is free to move with the rod if the latter should have any lateral motion or vibration. 80 Such movement of the casing will not impair the efficiency of the packing. The stuffing-box is made in two sections as stated in order that the parts inside thereof 85 may be put in place, and access to the casing for the purpose of replenishing the shot can be readily had upon removing the cap 9 and the plug 12.

I claim:

1. A rod-packing comprising a stuffing-box, a casing loose therein and surrounding the rod, and a packing inside the casing around the rod.

2. A rod-packing comprising a stuffing-box, a casing loose therein and surrounding the rod, a packing inside the casing around the rod, and packing-rings between the aforesaid packing and the end walls of the 95 stuffing-box.

3. A rod-packing comprising a stuffing-box, a casing loose therein and surrounding the rod, spaced packing-rings inside the casing, and a packing of spheres in the casing between the aforesaid packing-rings.

4. A rod-packing comprising a stuffing-box, a casing loose therein and surrounding the rod, spaced cup-shaped packing-rings inside the casing, conical packing-rings fitting the cupped ends of the aforesaid packing-rings, and a packing of spheres in the casing between the conical rings.

5. A rod-packing comprising a stuffing-box, a casing loose therein and surrounding the rod, spaced cup-shaped packing-rings inside the casing, spring-pressed conical 25
5 packing-rings fitting the cupped ends of the aforesaid packing-rings, and a packing of spheres in the casing between the conical rings.
6. A rod-packing comprising a stuffing- 30
10 box having on one side a neck provided with an opening communicating with the interior of the stuffing-box, a casing loose in the stuffing-box and having a tubular stem extending into the opening in the aforesaid 35
15 neck, a packing including a plurality of spheres inside the casing, and a spring-pressed follower in the aforesaid stem bearing on the spheres.
7. A rod-packing comprising a stuffing- 40
20 box having on one side a neck provided with an opening communicating with the interior of the stuffing-box, a casing loose in the stuffing-box and having a tubular stem extending into the opening in the aforesaid
- neck, spaced packing-rings inside the casing, a packing of spheres in the casing between the rings, and a spring-pressed follower in the aforesaid tubular stem bearing on the spheres.
8. A rod-packing comprising a stuffing- 30
box having on one side a neck provided with an opening communicating with the interior of the stuffing-box, a casing loose in the stuffing-box and having a tubular stem extending into the opening in the aforesaid 35
neck, spaced cup-shaped packing-rings inside the casing, spring-pressed conical packing-rings fitting the cupped ends of the aforesaid packing-rings, a packing of spheres in the casing between the conical rings, and a spring-pressed follower in the aforesaid tubular stem bearing on the spheres.

In testimony whereof I affix my signature, in presence of two witnesses.

THOMAS A. JOHNSTON.
